UNITED STATES PATENT OFFICE.

MAURICE L. HIRSCH AND HENRY J. HECTOR, OF RAVINIA, AND EMORY J. LEVY, OF HIGHLAND PARK, ILLINOIS, ASSIGNEES TO KINGLY SHIRT CO., OF CHICAGO, ILLINOIS, A CORPORATION OF ILLINOIS.

SHIRT.

Application filed October 22, 1924. Serial No. 745,091.

To all whom it may concern:

Be it known that we, MAURICE L. HIRSCH, HENRY J. HECTOR, and EMORY J. LEVY, citizens of the United States, residing at

5 Ravinia, in the county of Lake and State of Illinois; Ravinia, in the county of Lake and State of Illinois; and Highland Park, in the county of Lake and State of Illinois, respectively, have invented new and useful 10 Improvements in Shirts, of which the following is a full, clear, concise, and exact description, reference being had to the accompanying drawing, forming a part of this specification.

15 Our invention relates broadly to wearing apparel and has special reference to a shirt of a type known as the "closed front," that is, a shirt with an opening at the neck which requires slipping over the head to put it on.

20 An object of our invention is to provide a shirt of this type which opens a limited distance at the neck, say of such a length that a single button only is required to keep it closed, and then to attach a pleat to the shirt along the front and to extend it downwardly at least to a point below the waist line, so that it covers or conceals the opening and conveys the idea that the shirt opens the entire length down the front, and further to prevent the shirt from blousing or 25 pulling upwardly out of the trousers.

30 By our invention we are able to provide a shirt of the closed front type having the same appearance as one buttoning the entire way and yet secure the advantages of a closed front shirt. Moreover our shirt gains an additional advantage. When at sport or work requiring stooping or stretching, the closed front shirt heretofore used would 35 creep upwardly and blouse, and often pull free from the trousers. With this open type of shirt the sides or flaps would spread. Our shirt, however, overcomes these undesirable features. The pleat tends to hold the front of the shirt in place and admirably prevents blousing or pulling upwardly. Consequently we have found our shirt particularly useful for sport wear.

Other objects and advantages will appear from the following detailed description 50 when taken in connection with the following drawings which form a part hereof;

In the drawings:

Figure 1 is a view of a shirt embodying 55 our invention illustrating the appearance of it when worn by a person;

Fig. 2 is an enlarged detailed view illustrating the manner of reinforcing the shirt at the lower end of the opening in order to 60 provide a suitable hold for the stitching and thereby prevent the same from tearing loose;

Fig. 3 is an enlarged cross sectional view taken on line 3—3 of Fig. 1 at a point below the lower end of the opening;

Fig. 4 is a sectional view taken on line 4—4 of Fig. 1; and

Fig. 5 is an elevational view of a shirt embodying a slightly modified form of our invention.

By referring to the drawings, it will be noted that we embody our invention in a shirt having a body portion 2 provided with a closed front 3, an opening 4 at the neck and a center pleat 5. The opening 4 extends from the neck to a point indicated at 6, which is of such a distance that the shirt may be held closed by a single button 7. The usual collar button 8 is provided at the neck. Opening 4 is of such a size as to allow the shirt to easily slip down over the head, and preferably never extends below the waist line. Pleat 5 is sewed to the outer flap 8 of the shirt and extends over the opening 4. This pleat is preferably provided the entire length of the shirt front and tends to hide the opening 4. By extending the entire length of the shirt front, the shirt is provided with the appearance of an open shirt, which is buttoned the entire length.

The under flap 9 of the shirt comprises a pair of strips 10 and 11, which have their vertical edges folded back, and which are sewed to each other by means of the stitching 12 and 13. The shirt at this side of the opening is inserted between the strips 10 and 11 and sewed thereto by the stitching 13.

The outer flap 8, to which the pleat 5 is fastened comprises a strip 14 which is similar to the strips 10 and 11. The vertical edges of strip 14 are folded back in a manner similar to the vertical edges of either strips 10 and 11. The pleat 5 comprises a strip 15 having its edges 16 and 17 folded back and a reinforcing member 18 retained within the strip 15, the edges 16 and 17 being 5 turned back over the edges of the reinforcing member 18. Strip 14 is secured on the back side of the pleat 5 and is sewed thereto by means of the stitching 19 and 20. This side of the shirt adjacent to the opening 4 10 is inserted between the strip 14 and the pleat 5, and is sewed to these members by means of the stitching indicated at 20. The construction above described is employed along the edges of the shirt at the opening 4, the 15 pleat however running the entire length of the shirt. Pleat 5 comprises the strip 15 and the reinforcing member 18. This pleat preferably extends below the waist line and may terminate at the extreme lower end of the shirt. We have found that the strip 20 thus extended below the waist line will tend to prevent the shirt from blousing or pulling upwardly out of the trousers at the waist line. At the same time, the pleat serves to 25 give the shirt a finished appearance such as a shirt opening the entire length of the front has.

In order to provide a reinforcement for the flaps 8 and 9 where the opening 4 terminates at the lower end so that the stitching 30 will not pull loose if the shirt should be accidentally pulled at this point, we contemplate folding the lower ends of the strips 10 and 11 along a diagonal line, as indicated at 22, and then sewing the same by means of the stitching 23. At this point the strip 14 is likewise turned along a diagonal line 24 and sewed in a like manner by the stitching 24. The resulting triangular portions as seen in Fig. 2 are laid against each other and securely sewed together, thereby providing a fullness which suitably holds the stitching and prevents any strain on the shirt from ripping the stitching loose at this 40 point. This fullness, however, is not noticeable at the front of the shirt, inasmuch as the pleat 5 extends over the same and conceals it.

In Fig. 5, we have illustrated a shirt embodying our invention wherein the waist line is indicated by the dotted line 25 and the pleat 5 is shown as terminating at a point slightly below the same. We have found that we are able to obtain the advantages 50 of holding the shirt within the trousers as long as the pleat extends below this waist line. However, we prefer extending it to the extreme end of the shirt as indicated in Fig. 1.

Without further elaboration the foregoing

will so fully explain the gist of our invention that others may, by applying current knowledge, readily adapt the same for use under varying conditions of service, without eliminating certain features which may 70 properly be said to constitute the essential items of novelty involved, which items are intended to be defined and secured to us by the following claims.

We claim:

1. A shirt provided with a closed front having an opening therein from the neck to a point above the waist line, a button for closing said opening, a pleat for the center of said closed front extending below the waist line for imitating the appearance of a shirt provided with an open front, and a reinforcing member associated with said pleat tending to prevent the shirt from blousing at the waist line when worn. 75
2. A shirt provided with a closed front having an opening therein extending a limited distance from the neck, a button for closing said opening, and a pleat attached to said closed front so as to overlap said opening, said pleat provided to extend substantially the entire length of the shirt for imitating the appearance of a shirt with an open front, and a reinforcing member for said pleat for strengthening the same and preventing the shirt from blousing at the 80 waist line when worn. 90
3. A shirt having a closed front comprising a body portion extending below the waist line of the wearer and providing an opening at the neck which terminates a distance above the waist line, a pleat sewed to the shirt along a line parallel to the opening and extending substantially the entire length of said body portion, said pleat overlapping said opening and tending to conceal the same when the latter is closed, a strip sewed to the underside of said pleat and said shirt, similar strips sewed together and to the shirt at the opposite side of said opening and terminating at the lower end of the opening with their ends folded back and sewed together, said one strip also terminating at the lower end of the opening and likewise folded back at its end and then sewed, said folded back portions of said strips adapted to be placed together and sewed and serving to strengthen the shirt at said lower end of the opening, the fullness resulting from said folded back portions being covered by said pleat. 100
4. A shirt having a closed front comprising a body portion extending below the waist line of the wearer and providing an opening at the neck which terminates a distance above the waist line, a pleat sewed to the shirt along a line parallel to the opening and extending substantially the entire length of said body portion, said pleat overlapping said opening and tending to conceal 105
110
115
120
125
130

the same when the latter is closed, a strip sewed to the underside of said pleat in said shirt, said strip terminating at the lower end of the opening and folded back at this end 5 and then sewed, said folded back portion adapted to be sewed to said shirt at the opposite side of said opening and serving to strengthen the shirt at said lower end of

the opening, the fullness resulting from said folded portion being covered by said pleat. 10

In witness whereof, we have hereunto subscribed our names.

MAURICE L. HIRSCH.
HENRY J. HECTOR.
EMORY J. LEVY.
